UNITED STATES PATENT OFFICE.

WILLIAM P. SPRAGUE, OF SAN FRANCISCO, CALIFORNIA.

LIQUID-DISPENSER.

1,159,605.

Specification of Letters Patent.

Patented Nov. 9, 1915.

Application filed May 5, 1914. Serial No. 836,453.

To all whom it may concern:

Be it known that I, WILLIAM P. SPRAGUE, a citizen of the United States, and a resident of the city and county of San Francisco and State of California, have invented a certain new and useful Liquid-Dispenser, of which the following is a specification.

The invention contemplates an improved dispenser for dispensing liquids and particularly liquid soap.

Its advantages will be apparent from the disclosure.

In this specification and annexed drawing, I illustrate the invention in the form which I consider the best, but it is to be understood that I do not limit myself to such form because the said invention may be embodied in other forms, and it is to be understood that in and by the claims following the description herein, I desire to cover the invention in whatever form it may be embodied.

Referring to the drawing annexed to this specification and forming a part thereof: Figure 1 is a side view, partly in section and partly in elevation, of a dispenser embodying my invention. Fig. 2 is a view of a ring clamp for engaging the receptacle of the dispenser to support the receptacle. Fig. 3 is a perspective view of a perforated disk which rests in the upper end of the dispenser spout. Fig. 4 is a perspective view of a perforated disk adapted also to fit in the dispenser spout in coaptation with the disk shown in Fig. 3.

The dispenser comprises a receptacle which may be in the form of a glass globe 2, which is provided with a circumferential groove near its mouth in which is adapted to fit a split ring 3. The ends of the ring at the point where it is split have arms 4 and 5 extending therefrom, the inner faces of which are flat and lie adjacent each other when the ring is contracted while the outer faces thereof are semi-cylindrical so that then their flat faces are adjacent each other the two arms form a single cylindrical arm. The ring may be expanded so that it may be slipped over the mouth of the receptacle to the receptacle groove or removed from the groove and receptacle over the mouth thereof. The ring may be contracted into said groove so that the receptacle can turn in the ring, but cannot come out of it.

When the ring is contracted in the recep-

tacle groove and the arms 4 and 5 are brought together into cylindrical form, said arms are adapted to rest in a cylindrical opening in a bracket 6 which is attached to a wall or other support to support the dispenser on said bracket.

The receptacle 2 is provided with an exterior screw-thread *a* at its mouth on which thread screws an interiorly threaded cap 7, which cap has a downwardly projecting spout 8. The joint between the cap and the mouth of the receptacle is effectively sealed by a felt washer 9. The bore of said spout is conical in shape, converging slightly downwardly, the lower portion which forms a seat for the upper portion of a frustoconical valve plunger 14. Said seat and plunger form a valve for controlling the discharge of the liquid from the dispenser as will be hereinafter more fully set forth. The lower portion of said plunger projects downwardly below the lower end of the spout when the plunger is on its seat so that it may be pushed upwardly by the palm of the operator's hand to unseat it. The diameter of the bore of the spout and the diameter of the plunger are such that a considerable length of the upper part of the plunger seats itself upon a corresponding length of the bore of the spout, thus providing an elongated valve which effectively closes the lower end of the spout when in its closed position.

A disk 15 having a small opening 16 extending therethrough screws into an internal thread in the upper end of the bore of the spout. Said disk is provided with a groove 17 in its upper face for the reception of a screw driver to screw the disk into or out of the upper threaded end of the bore of the spout. A container for containing the liquid to be dispensed is formed by the receptacle 2, cap 7, and disk 15. A chamber 20 is formed within the spout between the upper end of the plunger 14 and the disk 15 for the reception of the liquid from the container. The opening 16 is of such size that the lower surface tension of the liquid in the container and the attraction of the liquid to the edge of the opening normally draws the lower surface of the liquid taut across the opening and closes the opening to the body of the liquid in the container so that the liquid normally will not flow out of the container through said opening. The

cap 7 is provided with an ear 12 having a screw threaded aperture therein in which screws a screw 13, which screw passes through the bracket 6 and screws into a 5 screw-threaded recess in the arms 4 and 5. Said recess is formed by forming part of it in the inner face of one arm and part in the inner face of the other arm and so that said parts register when said inner faces 10 are together. When the screw 13 screws through the ear 12, and extends through the bracket 6 and screws into the recess in the arms 4 and 5, it locks the cap and ring 3 to the bracket so that the cap cannot 15 screw off the mouth of the receptacle 2 and the receptacle 2 cannot come out of said ring. The screw may have any desirable head, but I prefer to countersink the aperture in the ear 12 and employ a screw having 20 a head which fits within said aperture, so that said screw which comprises the locking means for the dispenser is concealed.

In filling the receptacle 2, the screw 13 is first removed from the recess in the extensions 4 and 5. The receptacle 2 is then turned upside down on the bracket 6 until the mouth of the receptacle is at the top thereof, the cylindrical extensions 4 and 5 turning in the cylindrical opening in the 25 bracket as the fulcrum for the vessel. The cap 7 is then screwed off the mouth of the receptacle and the receptacle is filled with the desired liquid. When the receptacle is filled the cap is then screwed snugly onto 30 the mouth of the receptacle. The receptacle is then turned into upright position on its fulcrum so that the cap 7 is at the bottom of the receptacle and the spout 8 extends downwardly from the cap. The receptacle 35 is then turned to the right in the band 3 until the screw aperture in the ear 12 and screw recess in the extensions 4 and 5 register with the screw aperture in the bracket 6. The screw 13 which remains screwed in 40 the ear 12 is then screwed upwardly in the ear through the aperture in the bracket and screwed into the threaded recess in the extensions 4 and 5, whereby the dispenser is locked in its normal operative position.

I have provided means for varying the 45 amount of liquid discharged at each stroke of the plunger without varying the size of the plunger or spout. This is accomplished by means of one or more apertured frusto-conical disks 18 which seat in the bore of the spout 8 below the disk 15 with their apertures in registration with aperture 16 in disk 15 and vary volume of the chamber 20 in said bore. By placing the disks 18 in 50 or removing them from the bore of the spout 8, the length of the opening 16 is varied which varies the effect of the capillarity of the liquid flowing through said opening and consequently varies the amount of liquid 55 which flows through said opening from the

container into the chamber 20 as the plunger 14 drops, so that the amount of liquid flowing through said opening corresponds to the amount necessary for the particular volume of the chamber 20 in order that the dispenser may operate. By this means I am able to build one size dispenser and adjust it to dispense various amounts of liquid to meet various requirements of service.

The length of the spout and the length of 75 the plunger are such that when the plunger is elevated to its fullest extent the upper end thereof engages a disk 18, or the disk 16, if the disks 18 are not in the spout, which limit the upward movement of the plunger 80 so that the lower end thereof will project below the lower end of the spout when the plunger is elevated as well as when it is on its seat in its lowermost position. The lower end of the plunger therefore always 85 rests considerably below the lower end of the spout so that the operator's hand can never come into contact with the spout while pressing the plunger upward with his hand. The spout consequently always remains 90 clean and sanitary.

The discharging operation of my dispenser may be stated as follows: Assuming the dispenser to be in its normal operative position as shown in Fig. 1 of the drawing 95 with liquid in the container and only air in the chamber 20, in this condition of the dispenser the liquid does not flow out of the container through the opening 16, owing to the fact that the receptacle 2 is closed at the 100 top, to the surface tension of the liquid across said opening and to the upward atmospheric pressure against the liquid across said opening. It is believed, however, that the surface tension of the liquid and the upward pressure of the air in the chamber 20 are the controlling factors in preventing the liquid in flowing through said opening. The operator places the palm of his hand against the lower end of the plunger 14 and pushes 105 the plunger upwardly. The plunger, as it moves upwardly forces air in the chamber 20 up through the opening 16 and up through and above the liquid in the form of bubbles. The liquid, after the air passes through it, is prevented from flowing out of the container through opening 16 as above stated. The operator then removes his hand from the plunger, which drops by gravity upon its seat and closes the lower end of the spout 8, during which movement liquid flows from the container through the opening 16 into the chamber 20 and air enters the chamber from the atmosphere through the lower end of the spout. The liquid partially fills the chamber when the plunger has seated itself and rests upon the top of the plunger or lower wall of the chamber, while the air which enters the chamber from the atmosphere takes its position in the chamber 110 115 120 125 130

ber above the level of the liquid. In this condition of the dispenser the liquid in the container is prevented from flowing out through the opening 16 as above stated. 5 When the chamber is thus charged with liquid, the operator again pushes the plunger 14 upwardly off its seat with the palm of his hand and the liquid flows from the chamber 20 between the plunger and the inner wall of the spout 8 and out of the lower end of the spout.

As the plunger is pushed upwardly the latter time to discharge the liquid from the chamber out through the spout, it pushes 15 the body of liquid in the chamber upwardly and forces the air in the chamber above the liquid up through the opening 16 and up through and above the liquid in the container in the form of bubbles. As soon as 20 the air in the chamber passes up through the lower surface of the liquid in the container, and while the plunger is elevated and the liquid is flowing out of the chamber 20 through the lower end of the spout, liquid 25 is prevented from flowing out of the container through the opening 16 as above stated. When the liquid has passed out of the chamber through the lower end of the spout, the operator releases the plunger and 30 as it drops upon its seat the chamber is again charged with liquid and air and liquid is again prevented from flowing from the container through opening 16 as above stated.

35 The dispensing operation of the dispenser may then be repeated until all the liquid is dispensed from the container.

The unique construction of the plunger valve, *i. e.*, the slight convergence and elongation of its conical seating surface and its flat top which is normal to the axis of movement of the valve, give the valve when reciprocated, a positive and definite liquid ejecting action. The liquid and air in the 40 chamber 20 cannot escape through the lower end of the spout until the valve is elevated a substantial distance off its seat for the reason that the elongated passage formed between the plunger and the lower end of 45 the spout during the greater part of such movement is so narrow, that the liquid which enters said passage, closes the passage to the contents of the chamber. During the greater part of the upward movement of the 50 plunger, the air in the chamber 20 is therefore subjected to a direct and positive upward pressure which positively forces it with considerable pressure through the opening 16 and up through the body of the liquid in the container 2 to the top of the container. When the plunger valve has been 55 elevated sufficiently to establish an open 60 passage between the valve and its seat, further upward movement of the plunger valve causes the liquid in the chamber to be

pressed between the upper end of the plunger valve and the disk 18, or 16, which positively forces the liquid out of the chamber and the lower end of the spout through the passage between the valve and seat. When 70 the plunger is released and begins to descend, air enters the chamber 20 through the passage between the valve and its seat. When the plunger valve has partly descended the liquid, which adheres to the 75 valve and its seat, closes the passage between the valve and its seat so that during the latter part of the seating movement of the valve the passage between the valve and its seat is closed and a partial vacuum is 80 created in the chamber, into which liquid is forced from the container through the opening 16 by the pressure of the air on the top of the liquid in the container, and the chamber is charged with liquid to be dispensed. 85 It is not possible to discharge all the liquid from the container through the opening 16 and spout 8, simply by holding the plunger 14 off its seat, in view of the fact that during such condition the liquid is prevented 90 from flowing from the container through the opening 16 as above stated. Only a definite amount of liquid may be discharged from the dispenser while the plunger is elevated off its seat which is the charge of liquid in 95 the chamber 20.

The proper width of the opening 16 is of the utmost importance to the practical operation of the dispenser. If the opening is too large, the surface tension of the liquid 100 will not be strong enough to perform its part in preventing the liquid from flowing from the container through the opening 16, when it is necessary in the operation of the dispenser to keep the liquid in the container. 105 For definite, correct and easy operation of the dispenser, the width of the opening should be less than one eighth of an inch but the opening will not prevent operation of the device if larger than one-eighth inch 110 if the strength of the surface tension of the liquid be in proper proportion to the size of the opening. In practice, when ordinary liquid soap is dispensed, I have found that an opening of two millimeters in width gives 115 ideal results in the dispensing operation of the dispenser. The opening, however, will perform effective service with many liquids even though it be much smaller than the preferred size of two millimeters. In fact there 120 is scarcely a limit to which the width of the opening may be reduced without destroying its dispensing operation of many liquids. For liquids which have greater or less surface tension than liquid soap, the size of the opening 16 may be changed accordingly to 125 give ideal results without changing the principle of operation of the dispenser and without departing from the spirit of the invention.

I claim:

1. A liquid dispenser comprising a receptacle, means for supporting said receptacle, a cap for closing the mouth of said receptacle, said cap being detachable with relation both to said receptacle and said supporting means, a spout projecting from said cap, said spout having a slightly conical bore, said cap having a small opening for establishing communication between the receptacle and the bore of said spout, and a frusto-conical valve plunger movable in and adapted to seat in said bore for dispensing the liquid from said receptacle, said plunger extending below the end of the spout.

2. In a liquid dispenser, a container, a spout leading from said container having a bore which is lightly conical in shape at the discharge end, a disk screwed into the upper end of said bore, said disk being provided with an aperture through which liquid normally will not flow from said container, and a conical plunger movable longitudinally in and adapted to seat in said conical bore, said plunger adapted to project downwardly from said spout.

3. In a liquid dispenser, an inverted receptacle adapted to contain the liquid to be dispensed, a cap closing the mouth of said vessel, a spout on said cap, said cap having a small aperture therein communicating with said spout through which aperture liquid normally will not flow from said receptacle, a plunger movable longitudinally in said spout and adapted to seat therein, and means in said spout for varying the amount of liquid discharged from said receptacle through said aperture and spout for one operation of the plunger.

4. In a liquid dispenser, a container, a spout leading from said container and having a slightly conical bore therein, a disk having an aperture therein located in the upper end of said bore, said aperture being of such width that liquid normally will not flow therethrough from said container, a conical plunger movable longitudinally in and adapted to seat in said bore, said plunger being adapted to project below said spout, and a frusto-conical disk seated in said bore between the first named disk and plunger, said latter disk having an aperture which registers with the aperture in said first named disk.

5. In a liquid dispenser, a bracket, a retaining band seated in said bracket, a receptacle supported by said band, a cap independent of said band including a spout closing the mouth of said receptacle, means for discharging liquid from said receptacle through said spout, an ear on said cap, and a screw passing through said ear and engaging said bracket, whereby the cap is locked to the bracket.

6. In a liquid dispenser, a container, a

spout slightly conical in shape from top to bottom leading from said container, an elongated plunger conical in shape from top to bottom movable longitudinally in and adapted to seat in said spout and depending therefrom, and a wall having an aperture therein of less than one-eighth inch diameter located in the top end of the conical spout through which aperture liquid in said chamber flows only under the influence of said plunger.

7. In a liquid dispenser, a container for the liquid, a spout having a slightly conical bore therein, a frusto-conical disk having an aperture therein adapted to be seated in said spout, a disk fitting in the upper end of the bore of said spout above said first disk, said latter disk having an opening extending therethrough, the opening through both of said disks communicating with each other and forming a continuous passage through which liquid normally will not flow from said container, a valve in the lower end of said spout, liquid in said container being adapted to flow therefrom through said continuous passage and into said spout when said valve closes, said elongated passage being adapted to retard the flow of liquid from the container and said valve being adapted to control the discharge of the liquid from said spout.

8. In a liquid dispenser a container for the liquid, said container being provided with a small opening through which liquid normally will not flow from said container, means for causing liquid to flow through said opening from the container when desired and adjustable means for varying the length of said opening to vary the effect of capillarity of the liquid flowing through said opening.

9. In a liquid dispenser, a receptacle for liquid, a cap closing the mouth of said receptacle, means for discharging liquid from said receptacle, an arm connected to said receptacle, a bracket, said bracket provided with an opening adapted to receive said arm, said bracket and cap each provided with an aperture, the aperture in said cap being adapted to register with the aperture in said bracket and a locking element extending through said apertures and engaging said arm and locking the receptacle and cap to said bracket.

10. In a liquid dispenser, a receptacle for the liquid, a cap adapted to screw onto the mouth of said receptacle, means for discharging liquid from said receptacle, said receptacle provided with an annular groove, a split ring contracted in said groove, an arm extending from said ring, a bracket, said bracket being provided with an opening which receives said arm, said cap and bracket each provided with an aperture adapted to register with each other, and a

locking element extending through said apertures and engaging said arm and locking said receptacle and cap to said bracket.

11. In a liquid dispenser, a container for containing the liquid, a spout depending from said container provided with a slightly downwardly converging bore, said container being provided with a small aperture in its lower wall leading into said spout, a frusto conical plunger valve adapted to reciprocate and seat in the bore of said spout, said plunger valve adapted to extend below the lower end of said spout when on its seat and means for limiting the upward movement of said plunger valve so that it will still extend below the lower end of said spout when in its uppermost position.

12. In a liquid dispenser, a container for containing the liquid to be dispensed, a spout depending from said container provided with a slightly downwardly converging bore, said container being provided with a small aperture in its lower wall leading into said spout, a frusto-conical plunger valve adapted to reciprocate and seat itself in the bore of said spout, said plunger valve being adapted to extend below the lower end of said spout when on its seat, said apertured container wall being adapted to limit the upward movement of said plunger valve so that it will still extend below the lower end of said spout when in its uppermost position.

13. In a liquid dispenser, a closed top container for the liquid, a chamber depend-

ing from said container provided with a slightly downwardly converging bore, said container being provided with a small aperture in its lower wall leading into said chamber, a frusto-conical plunger valve piston adapted to reciprocate in said chamber to eject the liquid positively from said container out through the lower end of said chamber and to seat itself in said conical bore to prevent the liquid flowing out of the container through said spout.

14. In a liquid dispenser, a closed top container for the liquid, a chamber depending from said container provided with a slightly downwardly converging bore, said container being provided with a small aperture in its lower wall leading into said chamber, a frusto-conical plunger valve piston adapted to reciprocate in said chamber to eject liquid positively from said container out through the lower end of said chamber and to seat itself in said conical bore to prevent the liquid from flowing out of the container through said chamber, the seating portion of said valve piston in said bore being elongated so as to effectively close said chamber when said valve piston is on its seat.

In testimony whereof, I have hereunto set my hand at San Francisco, California, this 29th day of April 1914.

WILLIAM P. SPRAGUE.
